CLAIM

The ornamental design for an illuminated region of an external hard drive housing, as shown and described.

DESCRIPTION

FIG. 1 is a perspective view of an illuminated region of an external housing showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line showing of the remainder of the electronic housing and the stand, is for illustrative purposes only and forms no part of the claimed design.
